CONTAINER SEATING ABUTMENT FOR
RAILWAY CARS

Joel H. Mattern and Fred H. Pearce, Altoona,
Pa., assignors to The Pennsylvania Railroad
Company, Philadelphia, Pa., a corporation of
Pennsylvania

Application October 6, 1932, Serial No. 636,432

1 Claim. (Cl. 105—366)

This invention relates to railway cars of the type used for the transportation of shipping containers, and more particularly to seating abutments placed at the ends of a car and adapted to accommodate the corners of the end containers of the series.

Heretofore, where flat cars have been used for the transportation of containers, it has been customary to employ a series of guides or abutments arranged in spaced relation at the sides of the car platform to define a row of seats for the containers. Such guides or abutments usually extend to only a short distance above the car platform.

It being desirable to brace the end containers of the series against dislodgment incident to severe shocks, the principal object of our invention is to provide rigid abutments at the corners of the container car, such abutments extending upward to nearly half the height of the containers and defining seats for the accommodation of two corners of the end containers.

A further object of the invention is to provide in association with rigid container seating abutments of this character, safety appliances, in the form of hand holds mounted on the abutments, and hand rails connecting opposite abutments of a pair at the ends of the car.

Other more specific objects and advantages characteristic of our invention will become more fully apparent from the detailed description of one embodiment or example thereof which follows hereinafter having reference to the accompanying drawings.

Of the drawings:

Fig. I represents a perspective view of a railway container car of my invention with containers mounted at the ends of the car.

Fig. II represents a partial end elevation of the car shown in Fig. I.

Fig. III represents a side elevation of one corner of the car.

Fig. IV represents a plan view of the same; and, Fig. V represents a perspective view of one of the end corner abutments.

With particular reference to Fig. I of the drawings, there is shown an ordinary railway flat car 1 adapted for the carrying of less-than-carload-lot containers A. At spaced intervals along the sides of the car platform 2, abutments 3 extend upward only to a short distance above the car platform are provided. The abutments 3 define a series of rectangular seats for the accommodation of a row of containers arranged side by side on the car.

At each end of the car special container seating abutments 3a are provided in lieu of the ordinary shorter abutments 3 used for the seating of containers in the intermediate regions. As clearly shown in Figs. II, III and V, each end corner abutment 3a comprises an upstanding flat plate member 4 riveted to a side sill 5 of the car and an upstanding stiffening member 6 disposed transversely of the car platform. The stiffening member 6 in the present example of my invention is in the form of an angle bar and includes a transverse leg 7 and a longitudinal leg 8. As clearly shown in Fig. IV, the transverse leg 7 of the stiffening member 6 forms with the flat plate member 4 a right angular seat adapted for the accommodation of a corner of a container A. The longitudinal leg 8 of each stiffening member 6 is riveted to the flat plate 4. At its lower end each transverse stiffening member is attached to the side sill 5 of the car by a foot flange 9. At its upper end each transverse stiffening member 6 is beveled, as indicated at 10, the beveled portion being inclined upwardly and outwardly. Likewise the flat plate 4 of each container seating abutment 3a is beveled, as indicated at 11, the beveled portion being inclined upwardly and outwardly. The beveled portions 10, 11 of the stiffening member 6 and flat plate member 4, respectively, afford surfaces for guiding the containers as they are lowered into position on the platform 2 of the container car 1. In an obvious manner, when a container is lowered onto the car but is not exactly square in its position with relation to the seat which it is to occupy, its corners may strike the beveled portions 10, 11 of the abutments 3a, in which case the container will be guided in the proper direction so as to seat itself squarely within the right-angular pockets formed by the abutments 3a, as clearly shown in Fig. IV. For additional stiffening purposes, each seating abutment 3a is also provided with a gusset plate 12 of triangular formation which is riveted to the flat plate member 4 and to the side sill 5 of the car.

The end corner seating abutments 3a, in contrast to the intermediate abutments 3, extend upward, as shown in Fig. I, to nearly one-half the vertical height of the containers. Accordingly they serve to brace the containers disposed at the ends of the car 1 against dislodgment. While under ordinary conditions the relatively short intermediate abutments 3 are adequate to maintain the containers in position on the car, there may be instances where unusual shocks, such as the shock from a severe buffing force, cause a con-

tainer at the end of the car to topple over or to jar loose from its seat. The special end corner seating abutments 3a of this invention insure against any such dislodgment even when the car 5 is placed under very severe shock.

The members of each pair of end corner seating abutments 3a at each end of the car are connected together by a hand rail 13 which takes the place of the usual hand rail provided as a safety 10 appliance at the end of a flat car. The hand rail 13 is especially convenient when a man stands on the end of the car platform 2 outside of the container space, as for the purpose of operating the hand brake wheel shown at 14. The hand rail 15 13 also serves to rigidly join together the end corner abutments 3a and thus to prevent the flat plate members from spreading outward.

At each corner of the car there is provided a side step 15 of customary form. Above each side 20 step 15 there is a hand hold 16, one end of which is attached to the side sill 5 of the car, and the other end of which is attached to the flat plate member 4 of the container seating abutment 3a at that corner of the car. Two additional hand 25 holds 17, 18 are mounted on the flat plate member 4 of each container seating abutment 3a in substantially vertical alignment with the side step 15. Accordingly, at each corner of the car the side step 15 together with the hand holds 16, 17, 30 18, form a ladder by which a man can ascend to the platform 2. Moreover, the ladder thus afforded at each end of the car may be used to

advantage when it is necessary for a man to climb to the top of a container.

From the above description it will be apparent that the special end corner seating abutments 3a of this invention serve a number of useful purposes. They rigidly brace the end containers against toppling over; they provide a side ladder, at a point where such a ladder is especially useful; and they serve as anchorages for the ends of a hand rail in a particularly convenient manner.

While we have described one specific form which our invention may take, it will be obvious that various changes may be made in the structure here shown without departing from the spirit of our invention as defined in the annexed claim.

Having thus described our invention, we claim:

In a railway container car, end corner abutment for a container comprising flat plates attached to opposite side sills of the car and extending upward above the car platform to substantially one-half the height of the container, stiffening members extending transversely of the car platform and forming with said flat plates right-angular seats for the corners of a container, said flat plates and stiffening members having beveled ends for guiding a container corner into said seat, and a hand rail extending transversely of the car and joining together said end corner abutments. 100

JOEL H. MATTERN.
